UNITED STATES PATENT OFFICE.

THEODORE G. THOMAS, OF LAMARQUE, TEXAS, ASSIGNOR OF ONE-HALF
TO JAMES F. WARE, OF HITCHCOCK, TEXAS.

WRENCH.

SPECIFICATION forming part of Letters Patent No. 585,412, dated June 29, 1897.

Application filed September 17, 1896. Serial No. 606,120. (No model.)

To all whom it may concern:

Be it known that I, THEODORE G. THOMAS, a citizen of the United States, residing at La-
5
marque, in the county of Galveston and State
of Texas, have invented certain new and useful
Improvements in Wrenches; and I do
hereby declare the following to be a full, clear,
and exact description of the invention, such
as will enable others skilled in the art to
10 which it appertains to make and use the same.

This invention relates to a novel construc-
tion in a monkey-wrench, the object being to
provide a device of this kind which is readily
adjustable without the use of screws; and it
15 consists in the features of construction here-
inafter described and claimed.

In the accompanying drawings, illustrating
this invention, Figure 1 is a side elevation
20 of a monkey-wrench constructed in accord-
ance with this invention and showing in dotted
lines the position of the parts when the
jaws are open. Fig. 2 is a detail view of the
stationary member of a monkey-wrench, illus-
25 trating another embodiment of my invention.
Fig. 3 is a detail view of the movable mem-
ber of this modification.

In said drawings, 1 indicates the stationary
member, and 2 the movable member, of a
monkey-wrench, each being provided with
30 the usual jaws and connected by a guide fas-
tened to one and embracing the other.

In accordance with the principle involved
by this invention the members 1 and 2 are
each provided with handles 3, the inner faces
35 of which fit together when the jaws are in
operative position. The meeting faces of
these handles are provided with interfitting
or frictional contact-faces 4, and the outer
faces of the handle are inclined or wedge-
40 shaped, as at 5, so that the contact-faces of
the handles can be held forcibly together by
means of a ring 6 surrounding the handles.
The wedge or tapering faces 5 of the handle
are highest at their central portion and taper
45 toward each end thereof, and the combined

thickness of the highest and lowest portions
of these wedge-faces is less than the greatest
diameter of the ring 6, so that by placing
these faces opposite each other the ring can
be passed over the same and will be prevented 50
from falling therefrom by the thickness of
the wedges.

When it is desired to adjust the jaws, the
ring is first pushed toward the jaws and
around the low part of the wedge, whereupon 55
the meeting faces can be separated to allow
the jaw 2 and its handle to be moved rela-
tively to the other handle. When the jaws
are in the desired position, by wedging the
ring down upon the large part of the wedge- 60
faces the said jaws will be securely fastened
in this position.

It will be noted that by separating the mem-
bers of the monkey-wrench they can be used
as separate tools. For instance, the station- 65
ary member 1 can be used as a hammer.

In Fig. 1 of the drawings I have shown the
contact-faces between the handles 3 as con-
sisting of interfitting teeth 7, while in Figs.
2 and 3 the contact-faces consist of rough- 70
ened or serrated portions 8 on the handle.

Having thus described my invention, what
I claim as new, and desire to secure by Letters
Patent, is—

A monkey-wrench consisting of two rela- 75
tively movable members having jaws and in-
terfitting or contact faces, each of said mem-
bers being provided on its outer face with
wedge-faces consisting of a high portion in-
clined toward both ends of said member, and 80
a ring encircling said oppositely-inclined
wedge-faces, substantially as described.

In testimony whereof I have signed this
specification in the presence of two subscrib-
ing witnesses.

THEODORE G. THOMAS.
